US00D981190S

(12) **United States Design Patent** (10) **Patent No.:** **US D981,190 S**
Lee et al. (45) **Date of Patent:** **** Mar. 21, 2023**

(54) **SPOON**

(71) Applicant: **Kolor Magnetic (Shenzhen) Co., Ltd.**,
Guangdong (CN)

(72) Inventors: **Ching Mou Lee**, Guangdong (CN); **Chi
Wai Lee**, Guangdong (CN)

(73) Assignee: **Kolor Magnetic (Shenzhen) Co., Ltd.**,
Shenzhen (CN)

(**) Term: **15 Years**

(21) Appl. No.: **29/850,690**

(22) Filed: **Aug. 22, 2022**

Related U.S. Application Data

(63) Continuation-in-part of application No. 29/755,693,
filed on Oct. 22, 2020, now Pat. No. Des. 966,046.
